UNITED STATES PATENT OFFICE

KENNETH J. UNWIN, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

SIDE-SLIP WEFT DETECTOR

Application filed May 23, 1927. Serial No. 193,420.

This invention relates to weft detectors of the side slip type and it is the principal object of the invention to provide a detector of this form to cooperate with multi-color magazines to employ a minimum number of parts.

When detectors are applied to the usual form of multi-color magazines it is customary to connect the same with a controller pin which is normally in the path of an actuator lever which has a downward movement on each detecting beat of the loom. When weft is present the controller pin is withdrawn but when weft is absent the controller pin remains under the lever to interrupt downward movement of the same and thereby initiate replenishment. In copending application Ser. No. 190,091, filed by Frechett there is set forth a weft detector formed of a single piece of wire which is pivoted directly to the controller pin. In that application a pair of springs are set forth, one acting directly on the controller pin to move the same rearwardly and the other interposed between the controller pin and the detector to hold the latter in proper angular position with respect to its pivot so as to be engaged by the advancing supply of weft. In carrying out the Frechett construction it is necessary to employ a moving arm secured to a rock shaft around which lies a torsion spring, these parts being customary in the form of feeler set forth in patent to Ryon, No. 972,722. It is an important object of my present invention to retain all of the movements of the feeler set forth in the aforesaid application but with a reduction of the number of parts necessary and by the use of a single spring.

It is a further object of my invention to provide a sliding pin which is adjustably limited as to its rearward movement so as to determine not only the position of the controller pin but also the position of the detector. Said detector is preferably made of a single piece of wire which may be bent within limits and said wire is preferably pivoted to the controller pin so as to move back and forth therewith.

With these and other objects in view which will appear as the description proceeds, my invention resides in the combination and ar-

rangement of parts hereinafter described and set forth in the claims.

In the accompanying drawings wherein a convenient embodiment of my invention is set forth,

Fig. 1 is a top plan view of my detector certain parts being in section, the detector being shown in normal position in dotted lines and in non-indicating detecting position in full lines;

Fig. 2 is an end elevation looking in the direction of arrow 2, Fig. 1, certain parts being in section for the sake of clearness;

Fig. 3 is a front elevation taken in the direction of arrow 3, Fig. 1;

Fig. 4 is a view similar to Fig. 1 but showing the position the detector assumes when indicating weft exhaustion; and,

Fig. 5 is a detailed enlarged section on line 5—5 of Fig. 2.

Referring to the drawings I have shown a stand 10 provided with a vertical slot 11 extending substantially parallel to the length of the shuttle S and have indicated an actuator lever 12 the right end of which moves up and down in the slot 11. A hole 13 extends transversely across the slot 11 and receives the rear end of a controller pin 14 which under normal conditions lies under the actuator lever 12. So long as weft is present in sufficient quantity the controller pin 14 will be moved forwardly from under the lever 12 so that the latter will move downwardly without interruption but when the weft is substantially exhausted appropriate mechanism will operate to leave the controller pin 14 under the actuator lever so that downward movement of the latter is interrupted to initiate replenishment.

The matter thus far described is more fully set forth in patent to Ryon, No. 1,030,748, to which reference may be had. A support 20 is provided with a horizontal slot 21 through which extends a securing bolt 22, said bolt extending also through a vertical slot 23 formed in the foot 24 of a feeler bed 25. By means of the bolt and slots described vertical and horizontal adjustment of the feeler bed may be obtained.

Said bed has struck upwardly therefrom a pair of guides 26 and said bed is further

provided with a flange 27 receiving holes 28.

The detector is preferably formed of a single piece of wire 30 having the rear end formed as indicated in Figs. 1 and 4 with 5 weft engaging teeth 31. Said detector extends forwardly under the guides 26 and on the bed 25 and is bent as indicated in Fig. 1 to have a notch 32 and to extend laterally to the controller pin 14 as at 33. The forward 10 left end of said detector is bent downwardly as at 34 to extend through the controller pin and any convenient securing means as a cotter pin may be employed.

While the function of the controller pin is 15 the same as that set forth in the aforesaid patent to Ryon yet it is given a mounting unlike that set forth in the patent. In supporting the forward end of the controller pin I provide an upstanding arm 40 bolted at 20 41 to the support 20 and provide said arm with a bore through which the forward end of the controller pin extends. In this way I provide a sliding guide for the controller pin whereas in the patent previously mentioned and in the construction heretofore used the forward end of the controller pin has been held at the upper end of a pivoted arm. In order to limit rearward movement 25 of the controller pin I thread the forward end of the same as at 42 and provide the same with a pair of lock nuts 43 the rear one of which is adapted to engage the arm 40 to adjustably limit rearward movement of the controller pin. In order that the moving parts 30 previously described may be yieldingly held normally in rearward position I provide a single tension spring 50 the rear end of which is received by one or another of the holes 28 and the forward end of which is received 40 by the notch 32 of the detector. Said spring acts not only to hold the controller pin 14 yieldingly under the actuator lever 12 but also holds the detector 30 normally in the rearward dotted position shown in Fig. 1. 45 The effect of said spring is to turn the detector around the depending portion 34 as a pivot and this turning movement is limited by the left end of one or the other of the guides 26. As shown herein I have indicated 50 the rear guide as serving to stop left hand movement of the detector although the forward guide could perform the same function or if desired both parts could accomplish this result.

55 Under normal conditions the parts are in the dotted line position shown in Fig. 1 and when a sufficient supply of weft is on the bobbin B the parts will be moved forwardly to the full line position shown in said Fig. 1 60 against the action of spring 50. Under these conditions controller 14 will move forwardly and the actuator lever will be depressed without interruption. When insufficient weft remains on the bobbin B, however, the detector 65 will swing about the depending part 34 as a

70 pivot to assume the full line position shown in Fig. 4. Due to the action of spring 50 the detector will not only move along the bobbin but the controller pin 14 will remain in the path of the actuator lever 12 and downward movement of the latter will be interrupted to initiate replenishment.

75 Transfer mechanism indicated at T will move forwardly on the subsequent pick to engage the arm 33 of the detector and not only move the detector out of the path of the incoming bobbin but also move the controller pin 14 forwardly to prevent repetition of the indication.

80 From the foregoing it will be seen that I have provided a very simple side slip weft detector adaptable to multi-color magazines wherein the detector is preferably located on the magazine side of the loom. In will be seen that the controller pin is adjustably limited in its rearward movement and is formed with a pair of slide guides so that the same moves in a fixed path and it will further be seen that the single spring 50 serves the dual function of returning the detector to normal 85 position after both indicating and non-indicating detecting movements and also moves the controller pin to its normal position under the actuator lever 12. I do not wish to be limited to the particular mounting for the controller pin as it is apparent that the construction set forth is not the only means for holding the controller so that the same will not move to the right but will move in a path substantially perpendicular to the axis 90 of the shuttle so as to provide a pivot with the forward end of the detector such that the latter will always be properly placed with respect to the shuttle.

95 Having thus described my invention it will be apparent that changes and modifications may be made therein by those skilled in the art without departing from the spirit and scope of the invention and I do not wish to be limited to the details herein disclosed, but 100 what claim is:

110 1. In a side slipping weft detector for a loom having a regularly moving actuator to initiate replenishment and a weft surface to be detected, a controller normally in the path of the actuator, a weft detector pivoted directly to the controller and having a portion offset from the axis of the controller to engage the surface to be detected, and a single resilient means having one end fixed and the other end attached to the detector at a point between the pivotal connection thereof on the controller and the part to engage the weft surface to be detected, said controller and detector moving forwardly when weft is present 115 against the action of the resilient means and said detector sliding along the surface when substantially exhausted to have a pivotal movement with respect to the controller against the action of the resilient means. 120 125 130

2. In a side slipping weft detector for a loom having a regularly moving actuator to initiate replenishment and a weft surface to be detected, a controller normally lying in the path of movement of the actuator, a detector wire pivoted directly to the controller and having a rearwardly extending portion offset from the pivotal connection to engage the surface to be detected, and a single resilient means connected to the detector exerting a yielding pressure on the detector to move the latter toward the surface to be detected and also holding the controller yieldingly in the path of the actuator, said detector and controller moving forwardly against the action of the resilient means when weft is present and said detector moving laterally along and in contact with the surface when the latter is substantially exhausted against the action of the resilient means, the resilient means acting to hold the controller in the path of the actuator as the detector slides along a denuded surface.

3. In a side slipping weft detector for a loom having a regularly moving actuator to initiate replenishment and a weft surface to be detected, a stand, a controller slidably mounted on the stand and having a portion normally in the path of the actuator, a detector wire pivoted directly to the controller, and a single resilient element connected to the detector wire between the controller and the rear engaging end of said detector wire and acting to hold the detector and controller in normal rearward position and acting to return the detector to normal position after side slipping movement, said detector when in contact with sufficient supply of weft moving forwardly to move the controller out of the path of the actuator and said resilient means acting to hold the controller in the path of the actuator when the detector slides along and in contact with the substantially exhausted surface to be detected.

4. In a side slipping weft detector for a loom having a regularly moving actuator to initiate replenishment and a weft surface to be detected, a stand, a controller guided in the stand and having one end normally in the path of the actuator, means carried by the controller to limit movement thereof toward the actuator, a detector element pivoted directly to the controller and having a rearwardly extending portion offset from the controller to engage a surface to be detected, a single resilient means connected to the detector wire between the controller and the rear engaging end of said detector wire and acting on the detector to move the same to normal rearward position, and to restore the detector to normal position after angular movement, said yielding means serving also to hold the controller normally in the path of the actuator, and a stop acting to limit the movement of both the controller and de-

tector under the influence of the yielding means, said detector moving the controller forwardly out of the path of the actuator when in contact with sufficient supply of weft and said yielding means holding the controller under the actuator when the detector slides along the surface to be detected.

5. In a side slipping weft detector for a loom having a regularly moving actuator to initiate replenishment and a weft surface to be detected, a stand, a controller slidably mounted on the stand and having one end to cooperate with the actuator and the other end extending forwardly beyond the stand, stop means carried by the forwardly extending end of the controller to engage the stand and limit rearward movement of the controller, a detector element formed of a piece of wire pivoted directly to the controller and having a rearwardly extending weft surface engaging portion offset from the controller, and a single resilient means acting on the detector to hold the same yieldingly in rearward position and to restore the detector to normal position after angular movement, said yielding means also holding the controller in operative relation with respect to the actuator, the detector moving the controller forwardly out of the path of the actuator when in contact with a sufficient supply of weft and said yielding means holding the controller in the path of the actuator when the detector slides along a substantially exhausted supply of weft.

6. In a side slipping weft detector for a loom having a regularly moving actuator to initiate replenishment and a weft surface to be detected, a controller normally lying in the path of the actuator, a detector wire pivoted directly to the controller and having a portion offset from the latter to engage the surface to be detected, a stop to limit movement of the detector in a direction longitudinally of the shuttle, means to limit rearward movement of the controller pin, and a spring having one end fixed and the other end connected to the detector at a point between the pivotal connection between said detector and controller pin and the weft engaging surface of the detector, said spring exerting a pressure on the detector tending normally to hold the latter in normal rearward position against the stop and to restore the detector to normal position after angular movement and said spring also holding the controller yieldingly in the path of the actuator, said detector moving the controller out of the path of the actuator against the action of a spring when sufficient weft is present and said spring holding the controller in the path of the actuator when the detector slides along a substantially exhausted supply of weft.

In testimony whereof I have hereunto affixed my signature.
